(57) **CLAIM**

The ornamental design for an intervertebral implant, as shown and described.

DESCRIPTION

FIG. 1 is a side elevational view of an intervertebral implant illustrating the new design according to a first embodiment of the present invention;

FIG. 2 is a side elevational view of an intervertebral implant illustrating the new design according to a second embodiment of the present invention;

FIG. 3 is a side elevational view of an intervertebral implant illustrating the new design according to a third embodiment of the present invention; and,

FIG. 4 is a side elevational view of an intervertebral implant illustrating the new design according to a fourth embodiment of the present invention.
